DEWAXING HYDROCARBON OIL

Robert E. Manley, Beacon, N. Y., assignor to The Texas Company, New York, N. Y., a corporation of Delaware

Application June 13, 1932, Serial No. 616,865

11 Claims. (Cl. 196—17)

This invention relates to dewaxing hydrocarbon oil and more particularly to a process of removing paraffin wax from wax-bearing petroleum oil for the production of low pour test lubricating oil.

The invention broadly contemplates a process of dewaxing hydrocarbon oil wherein the cycle of operation comprises diluting wax-bearing oil with a low boiling hydrocarbon liquid having properties characteristic of propane, for example, and which may be gaseous under ordinary conditions of temperature and pressure, chilling this mixture to precipitate the wax constituents, separating the precipitated wax by filtration in the presence of a substantially dehydrated filter-aid material, separating from the filter-aid material the wax and moisture absorbed during dewaxing, and mixing this substantially moisture-free filter-aid material, advantageously after chilling, with further wax-bearing oil.

My invention contemplates diluting wax-bearing oil with a light hydrocarbon liquid composed of such constituents as propane, propylene, butane, and the like, and in suitable proportion with the oil to produce a solution from which the wax constituents may be readily precipitated upon cooling. The cooling may be effected by refrigeratively evaporating a portion of the low boiling hydrocarbon liquid directly from the mixture undergoing cooling. If desired, partial cooling of the mixture may be effected in this way while the final chilling may be accomplished by passing the partially cooled mixture in indirect heat exchange relationship with a refrigerant material. A part of the cooling may be effected by flowing the fresh wax-bearing mixture in heat exchange relationship with the outgoing cold dilute dewaxed mixture. In this latter case, a part or all of the low boiling diluent liquid may be evaporated with refrigerative effect from the dewaxed mixture during the exchange, and subsequently be recovered for use in diluting fresh wax-bearing oil, as described, for example, in my copending application, Serial No. 553,084, filed July 25, 1931, for "Dewaxing hydrocarbon oil."

When the wax-bearing mixture has been cooled to effect precipitation of the wax constituents, it is mixed with a substantially dehydrated filter-aid material of the type such as diatomaceous earth or other similar porous or fibrous filter-aid material, and which has advantageously been first subjected to cooling or chilling before admixing with the oil, as will subsequently be described in more detail.

The precipitated wax and solid filter-aid mate-

rial is then separated from the mixture by filtration. It may be of advantage during the filtering operation to evaporate a portion of the low boiling diluent hydrocarbon material from the mixture while adjacent the filtering surface to thereby effect cooling at the filtering surface, and thus prevent softening or re-solution of the wax.

The precipitated wax and solid filter-aid material, which is thus separated from the liquid hydrocarbons, is mixed with a liquid material adapted to displace the wax, as well as absorbed moisture, from the filter-aid material. Petroleum naphtha, for example, is particularly suitable for this purpose, although other wax solvents may be used. The removal of this moisture is necessary since, otherwise, its accumulation destroys the effectiveness of the material as a filter-aid medium, particularly in dewaxing operations where low temperatures prevail. This moisture is originally absorbed from the incoming oil and the surroundings. It must be continually removed, otherwise it accumulates in the material, forms ice during the dewaxing step, and thus reduces the porosity of the material and materially decreases its effectiveness as a filter-aid.

The filter cake is admixed with the solvent liquid to form a slurry or suspension, and is subjected to heating to a temperature at which the wax is maintained in a liquid solution, and such that moisture absorbed during the dewaxing step is displaced from the filter-aid material. The filter-aid material is advantageously separated from the slurry by filtration while maintaining the mixture in a hot condition. The separated filter-aid material may be washed with fresh warm solvent liquid to remove remaining oil or wax, following which the recovered material, now in a substantially completely dehydrated state, is subjected to cooling and chilling before mixing with further wax-bearing oil. This cooling may be accomplished, for example, by spraying the material with some of the low boiling hydrocarbon liquid which is refrigeratively evaporated in direct contact with the filter-aid material to thus cool it to a temperature approaching that of the chilled wax-bearing oil with which it is to be admixed.

My invention, therefore, comprises a cyclic process of dewaxing oils which involves diluting the oil with a liquid combining the properties of a wax-precipitating liquid medium with those of a refrigerating medium. The precipitated wax is then separated from this chilled mixture by filtration in the presence of a substantially moisture-free filter-aid material. The resulting filter

- cake is removed and the wax and the moisture, absorbed during the dewaxing operation, separated from the filter-aid material to thereby condition it for use in dewaxing further oil.
- 5 In order to more fully describe the invention, reference will now be made to the accompanying flow diagram, illustrating diagrammatically an arrangement of flow adapted to carry out my invention.
- 10 Wax-bearing oil from a tank 1 is delivered to a mixer 2 wherein it is diluted with low boiling hydrocarbon liquid, such as propane, butane, etc., delivered from a tank 3. The mixer 2 is provided with a stirring mechanism and is also 15 adapted to withstand pressure. If desired, a portion of the diluent liquid may be evaporated from the mixture with refrigerative effect at this point in order to bring about preliminary chilling of the mixture. The resulting vapor is led off 20 through a vent 4 to be recovered by compressing.
- The resulting mixture of wax-bearing oil and diluent liquid is drawn off from the mixer 2 through a chilling coil or heat interchanger 5 wherein the mixture may be brought into heat 25 exchange relationship with a stream of cold mixture from which the wax has been removed. The cooling effect may be further augmented by refrigeratively evaporating a portion or all of the diluent liquid from the dewaxed mixture during 30 passage through the exterior shell of the interchanger 5.
- The preliminarily cooled wax-bearing mixture is then introduced to a vessel 6 wherein further 35 cooling is advantageously effected by causing a portion of the diluent liquid to evaporate from the mixture. This evaporation may be effected by reducing the pressure or by applying a vacuum to the vessel, as the case may be. Liquid propane may be introduced to the bottom of this 40 vessel from the tank 3 through a pipe 7 and a branch pipe 8 to produce this internal cooling effect. The vapor evolved within the vessel is removed through a vent pipe and delivered to compressing means to be liquefied and cooled for 45 further use. The wax-bearing mixture may thus, for example, be cooled to a temperature of around +15° F. or lower within the vessel 6. Where materially lower temperatures are desired, it may be preferable to conduct this cold mixture 50 through a subsequent chiller 9, wherein the mixture flows in indirect heat exchange relationship with a refrigerant material. The refrigerant material may, for example, be propane, which is allowed to expand directly around the coils or 55 pipes through which the wax-bearing mixture is flowing.
- The finally chilled dilute wax-bearing mixture is withdrawn from the chiller 9 through a pipe 10 and delivered to a mixer 11 wherein it is 60 admixed with dehydrated filter-aid material, separated from the wax removed in a previous dewaxing cycle. The recovered filter-aid material, preferably after chilling or cooling, is introduced to the mixer through a chute 12. Suitable stirring means are provided within the mixer for 65 effecting complete mixing of the filter-aid material with the wax-bearing solution. If desired, additional propane liquid may be introduced to the mixer 11 through a pipe 13, either to increase 70 the degree of dilution, or for the purpose of supplying additional refrigeration by causing evaporation of such propane within the mixer in indirect contact with the wax-bearing mixture, the vaporized material being drawn off from the 75 mixer to compressing means for further use.
- The chilled mixture containing suspended wax and filter-aid material is removed from the mixer 11 by a pump 14 and delivered to a pressure filter 15 which may be, for example, of the pressure leaf or rotating drum type. Additional propane or diluent liquid may be mixed with the mixture as it enters the filter, or may be introduced into the filtering liquid within the filter shell or bowl, and caused to vaporize therein to obtain a chilling effect immediately adjacent the 10 filtering surfaces therein. The refrigeration supplied immediately adjacent the filtering surfaces in this way serves to maintain the filtering mixture at the desired low temperature and prevent softening or re-solution of the wax. Propane 15 vaporized within the filter shell is drawn off through a pipe 16 either to a compressor or to a gasometer.
- At the end of a filtering cycle, the filter 20 contents may be displaced and the filter cake dried by introducing additional propane to the filter wherein it is converted into gas and thus serves as a displacing and cake-drying medium.
- The filtrate removed from the filter is conducted through a pipe 19 to a stripper 20. However, all or a portion of this dewaxed filtrate may be first conducted through a pipe 21 to the exterior shell of the chilling coil 5 for the purpose of cooling the fresh incoming charge, as already described. From the shell of the chilling coil 5, it is returned through a pipe 22 to the stripper 20.
- The stripper 20 comprises a column containing suitable packing material, such as bubble trays, and is provided with a heating coil through which 35 heat may be supplied to the bottom of the stripper. It is also provided with a cooling coil near its top for supplying reflux thereto.
- The dewaxed filtrate is introduced to this stripper wherein the diluent liquid is removed. 40 The stripped dewaxed oil is removed from the bottom of the stripper while the diluent liquid, composed largely of propane with possibly small amounts of naphtha, is removed from the top of the stripper in the form of a vapor. This 45 vaporous material is delivered through a pipe 23 to compressing means, shortly to be described, to be recovered for further use.
- The filter cake formed during the filtering 50 operation is removed from the filter shell by a scroll 24 and discharged into a closed hopper or receiver 25. The receiver 25 communicates, by means of a chute 26, with the bottom of a closed vessel 27 into which the filter cake is introduced for treatment with a wax solvent or 55 displacing liquid. The vessel 27 is provided with suitable stirring mechanism as well as a heating coil. Naphtha is introduced to the vessel 27 through pipe 28 and mixed with the filter cake to form a slurry or suspension. The contents of the vessel are maintained at a temperature of around 160° to 200° F. or higher if necessary. It is contemplated that higher temperatures may be maintained as, for example, where it is desired to vaporize or distill off volatile matter including moisture. Under these conditions of 60 temperature, the naphtha exerts a solvent effect on the oil and the wax. The wax is thus displaced from the pores of the filter-aid material, as is also the water absorbed by the filter-aid material from the oil during the filtering and dewaxing step.
- Vapors evolved within the vessel 27 are led off through a pipe 29 to a tower 30 wherein naphtha constituents, water, etc., may be knocked back 75

and removed from the non-condensable portion. The condensed naphtha withdrawn from the tower 30 may be returned through pipe 31 to the vessel 21. The uncondensed vapors removed from the top of this tower, composed substantially of propane, are conducted through a pipe 32 to the gasometer 18.

The hot suspension of oil and wax and separated filter-aid material is withdrawn from the bottom of the vessel 21 by a pump 27a and conducted to the bowl of a rotating drum filter 33, adapted to operate under pressures either above or below atmospheric pressure. The mixture is advantageously maintained at a temperature of around 160° F. or 180° F. while in the filter bowl, and subjected to filtration under these conditions so that the wax is maintained in a liquid condition. The filter-aid material is deposited upon the exterior surface of a rotating drum 34 while the solvent naphtha and dissolved oil and wax are drawn through the surface into the interior of the drum as a filtrate. This filtrate is removed from the interior of the drum through a pipe 35 leading to a receiver 36. The filter-aid material is deposited on the surface of the rotating drum as a filter cake, and as the drum rotates is passed out of the filtering mixture through successive zones wherein it is dried to remove adhering filtering liquid, washed with fresh naphtha, dried to remove adhering naphtha, following which it is chilled and discharged from the filter, or discharged from the filter and then chilled prior to reuse. During passage through the cake washing zone, petroleum naphtha is introduced through a pipe 37 and heating coil 38, to a spray 39 positioned within the hood of the filter. By means of this spray, it is sprayed against the filter cake and drawn through the cake along with dissolved oil and wax to the interior of the drum 34. From the interior of this drum, it is withdrawn through pipe 40 to a receiver 41. The contents of the receiver 41 advantageously form the wax solvent supplied through pipe 28 to the vessel 27 for treating further filter cake.

The drying gas drawn through the filter cake during passage through the delivering zone is supplied to the hood of the filter through a pipe 42 from the gasometer 18.

The dried cake then passes into the chilling zone. This chilling or cooling is effected by introducing liquid propane through a pipe 43 from the tank 3 to a spray 44 within the hood of the filter. Propane is thus sprayed directly on to the filter cake, whereupon evaporation with refrigerant effect occurs, the evaporated propane being drawn through the cake into the interior of the drum from which it is removed through the pipe 40. The evaporation of the propane, in direct contact with the filter-aid material, not only cools and chills it but also materially aids in removing remaining particles of naphtha solvent as well as moisture.

The cake is then removed from the surface of the drum and discharged into the chute 12 leading to the mixer 11, previously referred to. If desired, the step of spraying the filter-aid material with refrigerant liquid while still on the filtering surface may be omitted. Instead, the filter-aid material may be chilled after being discharged into the chute 12 as, for example, by introducing liquid propane into the chute near its lower end and from which point the propane vaporizes and passes upwards through the chute in countercurrent contact with the descending filter-aid material.

The receivers 36 and 41 are provided with vapor outlets 45 and 46, respectively, leading to a knock-out box or trap 47. Trap 47 is advantageously provided with a barometric leg 48 by which means entrained liquid or foam is removed. Vapor or gas is removed from the trap 47 through a pipe 49 leading to a compressor 50 advantageously of the two-stage type.

The compressor 50 serves to reduce the pressure through the receiving drums to the interior of the rotating drum of the filter 33, and also takes care of excess propane vapor accumulating in the gasometer 18. The compressed vapors are delivered by the compressor 50 to a stripper 51 substantially similar to the stripper 20 already described.

The solution of oil and wax accumulating in the receiver 36 contains a certain amount of naphtha and propane. When vacuum is applied to the receiver through the pipe 46 vaporization of a substantial proportion of this propane and naphtha occurs, the vaporized material being drawn off to the compressor 50. A heating coil is advantageously provided within the bottom of the receiver 36 to supply heat which may be used to facilitate the separation of as much propane as possible at this point, as well as to maintain the wax in a liquid condition during the evaporation of the propane and naphtha. The wax solution is withdrawn from the bottom of the receiver 36 by a pump 52 and delivered through a pipe 53 to the stripper 51.

Heat is supplied to the bottom of the stripper in order to boil off the propane and naphtha which rises through the stripping column, and in doing so is subjected to rectification to effect separation between the propane and the higher boiling naphtha. The naphtha so separated is removed from a mid-point of the stripper through a pipe 54 to a receiving drum 55. This naphtha may be returned to the system either as a wash solution to the filter 33, or as a wax solvent to the vessel 27.

The separated propane is removed from the top of the stripper in vapor form through the pipe 56 to a compressor 57. The compressed vapor is then conducted through a cooling coil 58 wherein it is liquefied and from there returned through the pipe 59 to the storage tank 3.

The combined operation of dewaxing, recovering and reconditioning of filter-aid material is advantageously carried out in a closed system to avoid loss of propane, infiltration of air from the warm surroundings into the system, and to facilitate operations generally. In the practice of this invention, for example, about one part of wax-bearing lubricating distillate derived from Mid-Continent crude by vacuum distillation and having a viscosity of about 60 Saybolt universal seconds at 210° F. is mixed with about two parts of propane in the mixer 2, under a pressure sufficient to maintain the propane in a liquid condition. This mixture at a temperature of around 90° F. is then advantageously passed through the chilling coil 5 wherein it is cooled to a temperature of about +45° F. by heat interchange with the outgoing cold dilute dewaxed mixture.

The preliminarily cooled mixture is then delivered into the vessel 6 wherein it is cooled to about +15° or +20° F. by causing a portion of the diluent liquid to vaporize from the mixture or by introducing additional propane liquid into the mixture, which is allowed to vaporize with refrigerative effect. The mixture is maintained

at a dilution of from 50% to 70% of propane liquid. The final chilling of this mixture is then effected by passing the mixture through the chiller 9 wherein the temperature is reduced to about -30° F. At this temperature, the mixture is introduced to the mixer 11 and admixed with dehydrated and conditioned filter-aid material discharged from the filter 33.

While maintained at substantially this same 10 temperature, the dilute mixture, containing suspended wax and filter-aid material, is withdrawn from the mixer 11 and charged to the filter 15 to separate the suspended solid material. The filtrate is withdrawn and the diluent liquid removed therefrom by stripping, in the stripper 20, to produce a dewaxed oil having a pour test of 0° F. or lower.

The wax cake is removed from the filter and subjected to treatment, as already described, 20 to separate therefrom the filter-aid material which is reconditioned for mixing with further wax-bearing oil.

The invention is not restricted to dewaxing 25 viscous distillate wax-bearing stocks, but is also adapted to the treatment of various types of wax-bearing oils or fractions, including residual cylinder stocks, wax concentrates, and so forth.

While certain operating conditions have been 30 described in the foregoing example, it is contemplated that these conditions, particularly as regards temperature and pressure, may be varied to suit different requirements, and depending upon the nature of the wax-bearing oil undergoing treatment. Also, while the use of propane 35 has been specifically described, it is contemplated that various other hydrocarbon fractions of somewhat similar nature, including other liquid refrigerants which are gaseous under normal temperatures and pressures, and which are suitable as wax-precipitating media, may be employed.

Obviously, many modifications and variations 40 of the invention, as hereinbefore set forth, may be made without departing from the spirit and scope thereof, and therefore only such limitations should be imposed as are indicated in the appended claims.

I claim:

1. In a process of dewaxing hydrocarbon oil by filtration at low temperature in the presence of a substantially dehydrated inert comminuted solid filter-aid material, the method of reconditioning and dehydrating the filter-aid material for reuse comprising forming a suspension of the resulting filter cake in naphtha, heating the suspension to displace wax, oil and moisture from the filter-aid material, separating the filter-aid material while hot from the displaced matter, washing the separated filter-aid material with hot naphtha, and refrigeratively evaporating a volatile solvent liquid in direct contact with the washed filter-aid material to dissolve and remove adhering naphtha and to chill the filter-aid material prior to admixing with the cold wax-bearing oil.

2. In a process of dewaxing hydrocarbon oil by filtration at low temperature in the presence of a substantially dehydrated inert comminuted solid filter-aid material, the method of reconditioning and dehydrating the filter-aid material for reuse comprising forming a suspension of the resulting filter cake in a wax solvent, heating the suspension to displace wax, oil and moisture from the filter-aid material, separating the filter-

aid material while hot from the displaced matter, washing the separated filter-aid material with hot solvent, and refrigeratively evaporating a volatile solvent liquid in direct contact with the washed filter-aid material to dissolve and remove adhering wax solvent and to chill the filter-aid material prior to admixing with the cold wax-bearing oil.

3. In the process of dewaxing wax-bearing oil wherein the wax-bearing oil is chilled to 0° F. or 10 below by direct vaporization therefrom of a volatile refrigerant and solvent liquid, and the wax thus precipitated separated therefrom in the presence of an inert solid comminuted filter-aid material, the method of recovering and reconditioning the filter-aid material for reuse, comprising treating the mass of filter-aid material and adhering waxy matter with a wax solvent liquid at elevated temperature adapted to dissolve the waxy matter and displace it from the filter-aid material, separating the filter-aid material from the resulting mixture while maintaining the mixture at elevated temperature, washing the separated filter-aid material with hot solvent to remove remaining impurities, and vaporizing a portion of 20 the volatile refrigerant in a direct contact with the washed filter-aid material to dissolve and remove adhering solvent liquid and to thereby cool the filter-aid material to a temperature of around 0° F. or below suitable for admixing with further cold wax-bearing mixture.

4. In the process of dewaxing wax-bearing oil wherein the wax-bearing oil is chilled to 0° F. or 25 below, by direct vaporization therefrom of a refrigerant material comprising essentially propane, 30 and the wax thus precipitated separated therefrom in the presence of an inert solid comminuted filter-aid material, the method of recovering and reconditioning the filter-aid material for reuse, comprising mixing the mass of filter-aid material 35 and adhering waxy matter with a solvent liquid adapted to dissolve the waxy matter and displace it from the filter-aid, heating the resulting mixture whereby propane contained in the wax and filter-aid material is vaporized and recovered, 40 separating the filter-aid material from the remaining hot mixture, washing the separated filter-aid material with fresh solvent liquid, and vaporizing propane in direct contact with the washed 45 filter-aid material to dissolve and remove adhering solvent and to thereby chill the filter-aid material to a temperature around 0° F. or below suitable for admixing with further cold wax-bearing mixture.

5. In the process of dewaxing wax-bearing oil 50 wherein the wax-bearing oil is chilled to 0° F. or below, by direct vaporization therefrom of a refrigerant comprising essentially propane, and the wax thus precipitated separated therefrom in the presence of an inert solid comminuted filter-aid material, the method of recovering and reconditioning the filter-aid material for reuse, comprising mixing the mass of filter-aid material and adhering waxy matter with naphtha adapted to 55 dissolve the waxy matter and displace it from the filter-aid, heating the resulting mixture to a temperature of from about 160° to about 200° F. whereby propane contained in the wax and filter-aid material is vaporized and recovered, 60 separating the filter-aid material from the remaining hot mixture, washing the separated filter-aid material with fresh naphtha, and then further washing it with vaporizing propane to 65 dissolve and remove adhering naphtha and to cool 70

the filter-aid material for admixing with further cold wax-bearing mixture.

6. In the process of dewaxing wax-bearing oil wherein the wax-bearing oil is chilled to 0° F. or below, by direct vaporization therefrom of a refrigerant material comprising essentially propane, and the wax thus precipitated separated therefrom in the presence of an inert solid comminuted filter aid material, the method of recovering and reconditioning the filter-aid material for reuse, comprising mixing the filter-aid material and adhering waxy matter with naphtha, heating the resulting mixture whereby propane contained in the waxy matter and filter-aid material is vaporized and recovered, subjecting the remaining mixture to filtration at a temperature of from 160° to 200° F. to remove the dissolved waxy material and form a filter cake of filter-aid material, washing the resulting filter cake with hot naphtha to remove adhering impurities, and spraying the washed cake with a liquid hydrocarbon comprising essentially propane to remove adhering naphtha and to cool the filter-aid material for admixing with further cold wax-bearing oil.

7. In dewaxing wax-bearing oil wherein solidified wax is separated from the oil in the presence of a solid inert comminuted filter-aid material, the wax dissolved and removed from the filter-aid material by treating the filter-aid material and adhering wax with a solvent liquid for wax, and the filter-aid material conditioned for reuse, the steps consisting in contacting the solvent-treated filter-aid material with a volatile solvent liquid and refrigeratively evaporating a portion of said liquid in direct contact with said filter-aid material thereby washing retained wax solvent liquid from the filter-aid material and precooling it for reuse with fresh wax-bearing charge.

8. In the process of dewaxing wax-bearing mineral oil wherein the wax is separated from cold dilute wax-bearing oil in the presence of a solid inert comminuted filter-aid material, the method of cooling the filter-aid material prior to its addition to the wax-bearing oil, comprising refrigeratively vaporizing a low-boiling hydrocarbon liquid comprising propane in direct contact with the filter-aid material whereby it is chilled to substantially the temperature desired for dewaxing the oil.

9. In a dewaxing process wherein a wax-bearing mixture is chilled by direct vaporization therefrom of a volatile refrigerant material of the character of a light low-boiling petroleum fraction and the wax thus precipitated separated from the cold mixture in the presence of an inert solid comminuted wax-adherent material, the method of cooling the wax-adherent material prior to its addition to the wax-bearing mixture comprising refrigeratively evaporating a portion of the refrigerant material in direct contact with the wax-adherent material whereby it is chilled to substantially the temperature desired for dewaxing the oil.

10. In the process of dewaxing wax-bearing oil wherein the wax-bearing oil is chilled to 0° F. or below by direct vaporization therefrom of a liquefied normally gaseous diluent, the wax thus precipitated separated therefrom in the presence of an inert solid comminuted filter-aid material, the wax dissolved and removed from the filter-aid material by treating it with a solvent liquid for wax, and the filter-aid material conditioned for reuse, the steps consisting in contacting the filter-aid material with some of the liquefied normally gaseous diluent and refrigeratively evaporating a portion of said liquid in direct contact with said filter-aid material thereby washing retained wax solvent liquid from the filter-aid material and precooling it for reuse with fresh wax-bearing charge.

11. In the process of dewaxing wax-bearing oil in which the wax-bearing oil is chilled to 0° F. or below by direct vaporization therefrom of a liquefied normally gaseous hydrocarbon, and the wax thus precipitated separated therefrom in the presence of an inert solid comminuted filter-aid material, the steps consisting in contacting the filter-aid material with some of the liquefied normally gaseous hydrocarbon, refrigeratively evaporating at least a portion of said liquid in direct contact with said filter-aid material to thereby cool the same, and admixing the cooled filter-aid material with the previously chilled wax-bearing mixture.

ROBERT E. MANLEY.
